UNITED STATES PATENT OFFICE.

LEE DANIELS, OF PLACERVILLE, CALIFORNIA.

ROTARY PUMP.

No. 893,454.

Specification of Letters Patent. Patented July 14, 1908.

Application filed August 1, 1906. Serial No. 328,782.

To all whom it may concern:

Be it known that I, LEE DANIELS, a citizen of the United States, residing at Placerville, in the county of Eldorado and State of California, have invented new and useful Improvements in Rotary Pumps, of which the following is a specification.

My invention relates to rotary pumps of the type including an eccentrically mounted piston and an independently movable gate.

The primary object of my invention is to provide means whereby the piston may be readily and quickly adjusted to compensate for any wear thereof.

With the above and other objects in view, the invention consists of the construction, combination and arrangement of parts hereinafter fully described, claimed and illustrated in the accompanying drawings, where-

20 in:
Figure 1 is a vertical transverse section of a pump constructed in accordance with my invention. Fig. 2 is a vertical longitudinal section thereof. Fig. 3 is a sectional view 25 taken longitudinally through the cylinder on the plane indicated by the line 3—3 of Fig. 1, the cylinder, heads, piston and gate being omitted. Fig. 4 is an end view of the piston. Fig. 5 is a sectional view taken longitudinally through the piston on the plane indicated by the line 5—5 of Fig. 4. Fig. 6 is a 30 detail perspective view of the gate, the packing blades being omitted. Fig. 7 is a detail view in front elevation of the stuffing box, the cap-nut, gland and packing being omitted. Fig. 8 is a vertical central section therethrough. Fig. 9 is a detail view in rear elevation of the thrust bearing, the stem being removed, and Fig. 10 is a vertical 35 central section therethrough.

Referring to the drawings by reference numerals, 2 designates an open ended cylinder, and 3—4 the heads thereof. The cylinder 2 is formed with vertical flanges 5, and the heads 3—4 are formed with horizontal flanges 6 which are adapted to engage over the flanges 5 when the heads are in applied position. The heads are secured in position by bolts 7 and nuts 8, the bolts being passed through the flanges 5 and the heads. The cylinder 2 is provided with an intake port 9 and a discharge port 10 which communicate with longitudinally extending recesses 11 formed in the inner wall of the cylinder,

which inner wall is also formed with recesses 55 12. The recesses 12 extend from one side wall of each recess 11 and gradually diminish in depth and merge at their opposite ends into the inner wall of the cylinder 2. The cylinder 2 is formed with coupling bosses 60 13—14 inclosing respectively the ports 9—10 and having respectively connected therewith a discharge pipe 15 and a supply pipe 16. A longitudinally extending flange 17 is formed upon the under side and exteriorly of 65 the cylinder 2, and provides means by which the pump may be secured to a suitable base or support. The flange 17 is strengthened and braced by a web 18 formed upon the under side of the cylinder and extending from 70 the coupling boss 14 to the flange.

The heads 3—4 are provided with longitudinally aligned and eccentrically arranged openings 19, and with a plurality of screw-threaded openings 20 arranged in planes concentric with the openings 19. A thrust bearing 21 is formed at a point intermediate its ends with an annular flange 22, the location of the flange providing a boss 23 which is adapted to be received by the opening 19 in 75 the head 4. The flange 22 is provided with a number of segmental openings 24 which are arranged in a concentric plane, and through the medium of which the thrust bearing is adjustably secured in applied position by 80 bolts 25 passed through the opening 24 and threadedly engaged with the openings 20 in the head 4. The bearing opening 26 of the thrust bearing is eccentrically arranged with 85 relation to the plane in which the openings 24 are located. A stuffing box 27 is formed at a point intermediate its ends with an annular flange 28, the location of said flange providing a boss 29 adapted to be received by the opening 19 in the head 3. The flange 28 is 90 provided with a number of segmental openings 30 which are arranged in a concentric plane, and through the medium of which the thrust bearing is adjustably secured in applied position by bolts 31 passed through the 95 openings 30 and threadedly engaged with the openings 20 in the head 3. The bearing opening 32 of the stuffing box is eccentrically arranged with relation to the plane in which the openings 30 are located. A shaft 33 is 100 journaled in the bearing openings 26 and 32 of the thrust bearing and stuffing box, respectively. A suitable packing 34 and a

gland 35 are mounted within the stuffing box 27, and a cap-nut 36 has threaded engagement therewith.

A piston 37 is fixed upon the shaft 32, and it consists of two approximately semi-cylindrical sections 38 which are secured to a hub 39 by spokes 40 in a manner to provide two diametrically opposed and longitudinally extending openings 41, said openings being provided to adapt the piston for the reception of a radially movable gate 42. The gate 42 comprises two sections 43, recessed as at 44, for the reception of the spokes 40. The outer edges of the sections 42 are provided with longitudinally extending recesses 45 adapted for the reception of packing blades 46, said blades being yieldingly held in engagement with the inner wall of the cylinder 2 through the medium of springs 47 located within the recesses 45 behind the packing blades.

In order to limit the thrust of the shaft, an adjustable stop 48 is provided, which is carried by a screw-threaded stem 49, said stem being adjustably mounted in a screw-threaded opening in the extension 50 of the thrust bearing 21 and projected exteriorly therefrom and provided with an angular head 51 for the reception of a wrench or other tool by which the stem may be adjusted. By means of the adjustability of the stem, the stop carried thereby may be inwardly or outwardly moved to limit the longitudinal thrust of the shaft and to take up any wear that may occur in the opening of the bearing.

In view of the fact that the piston 37 is eccentrically mounted within the cylinder 2, a portion of the piston is at all times in contact with a portion of the inner wall of the cylinder. In order to take up any wear that may occur either the inner wall of the cylinder or the piston, the shaft 33 may be adjusted through the medium of the thrust bearing 21 and the stuffing box 27, this adjustment being permitted through the medium of the segmental openings 24 and 30 located respectively in the flanges of the thrust bearing and stuffing box.

From the foregoing description taken in connection with the accompanying drawings, the construction and mode of operation of the invention should be understood without a further extended description.

Changes in the form, proportions and minor details of construction may be made within the scope of the claims without de-

parting from the spirit or sacrificing any of the advantages of the invention.

Having fully described and illustrated my invention, what I claim is:

1. A rotary pump having a cylindrical casing open at its ends, heads secured on said ends and removable therefrom, a shaft having its bearings in said heads, a cylindrical piston in said casing and on said shaft, said piston comprising a pair of approximately cylindrical sections spaced apart to form radial openings between them, a hub portion and spokes midway between the ends of the said sections and connecting them to the hub section, and a gate comprising two sections, arranged end to end, disposed in the openings between the sections of the piston and having recesses in their opposing ends clearing the spokes.

2. A rotary pump including a cylinder provided with an intake port and a discharge port, heads closing the ends of the cylinder and each formed with a concentric opening, a stuffing box having a concentric sleeve extension to fit within the opening in one of the heads, said box having a flange overlying and bearing against the surface of the head, the stuffing box being formed with an interior bearing opening arranged eccentrically to the outer surface of the box, and means engaging the flange of the box and head to limit the movement of the box relative to the head.

3. A rotary pump including a cylinder provided with an intake port and a discharge port, heads closing the ends of the cylinder and each formed with a concentric opening, a stuffing box having a concentric sleeve extension to fit within the opening in one of the heads, said box having a flange overlying and bearing against the surface of the head and formed with a series of concentrically arranged slots, the stuffing box being formed with an interior bearing opening arranged eccentrically to the outer surface of the box, and means passed through the slots in the flange and engaging the head, whereby to adjust the box relative to the head.

In testimony whereof, I affix my signature in presence of witnesses.

LEE DANIELS.
